UNITED STATES PATENT OFFICE.

THOMAS K. BENTON, OF BLOOMFIELD, NEW JERSEY, ASSIGNOR TO THE COURVOISIER, WILCOX MANUFACTURING COMPANY, OF NEW YORK.

WATCH-CASE SPRING.

SPECIFICATION forming part of Letters Patent No. 430,824, dated June 24, 1890.

Application filed February 20, 1890. Serial No. 341,119. (No model.)

To all whom it may concern:

Be it known that I, THOMAS K. BENTON, residing in Bloomfield, Essex county, New Jersey, have invented certain new and useful 5 Improvements in Watch-Case Springs, of which the following is a specification.

This invention relates to improvements in lock and fly springs for watch-cases; and it has for its object to facilitate the insertion of 10 said springs into the watch-case.

The invention consists in the novel details of improvement and the combination of parts that will be more fully hereinafter set forth, and then pointed out in the claims.

15 Reference is to be had to the accompanying drawings, forming part of this specification, wherein—

Figure 1 is a partly-broken face view of a watch-case containing my improvements. 20 Fig. 2 is a cross-sectional view of the same; and Figs. 3, 4, and 5 are detail views of my improvements, more fully hereinafter explained.

In the accompanying drawings, the letter 25 A indicates a portion of a watch case, and B is its stem.

D is a lock or fly spring that fits within the case A and holds the watch-cover (not shown) closed or open. The spring D is curved to 30 conform to the curve of the case A, and it has secured to it a back piece E. Screws a, that pass through the case A and enter the back piece E, hold the latter, and thereby the spring D, within the case A. To place the spring D, within the case A. To place the spring D, into position in the case A, it should bent or 35 its ends moved toward each other (as in full lines, Fig. 4) to shorten the arc to permit its free entry. If the back piece E were one continuous piece of metal secured to the spring D, said spring could not be properly bent, and therefore to place the spring D within the case would require much exertion and danger of scratching or injuring the case. To 40 overcome this difficulty, I sever or separate the back piece E, preferably about midway of its length, as at b, as clearly shown in the drawings. The inner or severed parts of the back piece E are free or disconnected from the spring D, (see Fig. 4,) which leaves the 45 spring D free to bend opposite the severed

part b of the back piece E. The back piece E at or near its outer ends may be secured to the spring D by rivets or solder.

When the spring D is bent to insert it in the case A, the severed ends b of the back 55 piece E move outward slightly, as in Fig. 4, which gives freedom to the spring D in bending.

When the spring D is to be placed in the case A, it is first bent, as in Fig. 4, to shorten 60 the arc or reduce the size of the spring, the inner severed ends of the back piece E permitting the bending of the spring, as before stated. The spring is then passed into the case A, and as the arc of the spring is now 65 less than the arc of the case A it is free to enter the same. The ends of the springs are now released, when it will expand to its proper size, and thus fit snugly within the case A. The screws a being next passed into the back 70 piece E, the spring will be firmly held in the case.

Springs constructed according to my invention can be placed in the case with much greater speed and ease than where a continuous 75 back piece is used, said latter back piece being so stiff as to prevent the spring D bending to permit its easy and quick insertion in the case. The stem B in Fig. 2 is shown connected to the end of the lock-spring D, as 80 usual. The fly-spring is also to be constructed as before stated.

Having now described my invention, what I claim is—

1. The spring D, combined with the back 85 piece E, secured to the same at certain points and separated transversely between its ends and disconnected from the back piece near its separated parts, substantially as described.

2. The spring D, combined with the back 90 piece E, that is secured to the spring D near its outer ends and disconnected therefrom at its central part, substantially as described.

3. The spring D, combined with the back 95 piece E, that is secured thereto and separated or severed as at b, substantially as described.

THOMAS K. BENTON.
